Primary Examiner — Mary Ann Calabrese*Assistant Examiner* — Katelin G Kloberg(74) Attorney, Agent, or Firm — Raymond Y. Chan;
David and Raymond Patent Firm(57) CLAIM

The ornamental design for a pet life jacket, as shown and described.

DESCRIPTION

FIG. 1 is a perspective view of the pet life jacket showing my new design;

FIG. 2 is a right view thereof;

FIG. 3 is a left view thereof;

FIG. 4 is a top view thereof;

FIG. 5 is a bottom view thereof;

FIG. 6 is a front view thereof;

FIG. 7 is a rear view thereof;

FIG. 8 is a perspective view of the pet life jacket being worn by a pet; and,

FIG. 9 is a top view of the pet life jacket being laid flat. The broken lines represent unclaimed portions of the design article. All of the broken lines forms no part of the claimed design.

1 Claim, 9 Drawing Sheets(56)
